COLLAR

Max M. Newman and Victor M. Newman,
New York, N. Y.

Application January 5, 1944, Serial No. 517,036

4 Claims. (Cl. 2—132)

1

Our invention relates to a new and improved collar, which can be affixed to a shirt, or which can be sold as a detachable collar. The invention relates particularly to an improvement in the outer band or face band of a collar of the familiar type, in which an outer band is attached to an inner band or neckband, at the top fold line of the collar.

According to our invention, we provide the corners of the outer band or face band of the necktie, with flexible chain weights, so that said corners remain straight and lie properly, even if the collar is unstarched. By using flexible chain weights which have little or no inherent stiffness, instead of non-bendable wires or the like, we provide a face band whose points remain properly extended so as to present a neat appearance, and the corners remain freely bendable, so that the collar can be laundered by hand or by machine, in the usual manner.

Numerous additional objects of our invention are stated in the annexed description and drawings which illustrate preferred embodiments thereof.

Fig. 1 is a partial front elevation of the outer band or face band of a collar, which illustrates how the flexible chains are connected to said face band, at its corners. In this view, part of the representation of the lining layer of said face band of the collar has been omitted.

Fig. 2 is a section on the line 2—2 of Fig. 1.

Fig. 3 is a partial elevation of the completed face band, after it has been turned from the initial stage which is shown in Figs. 1 and 2.

Fig. 4 is an enlarged section on the line 4—4 of Fig. 3.

Fig. 5 is a view, similar to Fig. 1, illustrating a modified method of making the face band of the improved collar.

Fig. 6 is a section on the line 6—6 of Fig. 5.

Fig. 7 is a similar view to Fig. 3, showing the finished face band which is made according to said modified method.

Fig. 8 is an enlarged section on the line 8—8 of Fig. 7.

Fig. 9 is a partial front elevation of a finished collar.

Fig. 10 illustrates a modification, in which the chain is connected to a flexible tape, and said chain and its tape are then connected to the face band of the collar.

Fig. 11 shows the sub-assembly of the flexible chain and the flexible tape.

Fig. 12 is a section on the line 12—12 of Fig. 11.

2

Fig. 13 is an enlarged section of the embodiment of Figs. 10—12, similar to Figs. 4 and 8.

In the first embodiment of Figs. 1—4, the fabric layer 11 is the final outer layer of the finished face band F, the fabric layer 10 is the final inner layer of said finished face band, and the fabric layer 12 is the final intermediate layer or lining layer of such finished face band.

Said fabric layers 10, 11, and 12 are first assembled as shown in Fig. 2, with the layer 11 located between layers 10 and 12, and two chains 13 located at each corner C of said assembly. Each chain 13 is thus located between the layers 11 and 12.

These initially assembled fabric layers are stitched together at the bottom edge B of said assembly and at each upstanding edge E of said assembly, by means of two parallel rows of stitches 14. Each chain 13 is thus frictionally held at the respective corner C, against shifting relative to the layers. Each chain 13 is of maximum flexibility, and it is made of very fine links, bars, etc., so that it is as flexible, or almost as flexible, as the assembled layers. Since the links or other elements of each chain 13 are pivotally connected to each other, said chains 13 impart little or no stiffness to the layers at the corners C.

The initial assembly, whose parts are thus connected by the stitches 14, is free from stitches or other connecting means at the top of such initial assembly.

This initial assembly is then turned so that the lining layer 12 is finally located between layers 10 and 11, as shown in Fig. 4, which illustrates the finished face band F, which is ready for attachment to the neckband of the collar.

In the completed faceband F, the inner layer 10 has an inturned edge-portion at each upstanding edge E, and the layers 11 and 12 having inturned abutting edge-portions at each said edge E. Each chain 13 at each corner C, is located between the inturned edge-portion of inner layer 10, and the inturned edge-portion of layer 11. The same edge-construction is produced at the bottom-edge B of the finished face band F.

According to the modified method which is illustrated in Figs. 5—8, the layers 10, 11 and 12, initially assembled as shown in Fig. 6, are stitched to each other at each upstanding edge E and the bottom edge B, by a single line of stitches 14. The top edges of said layers 10, 11 and 12 remain unconnected to each other, as in the first embodiment.

The initial assembly of Fig. 6 is then turned, so as to locate layer 12 between layers 10 and 11. Two chains 13 are then inserted at each corner C, so that said chains 13 are associated with the layers in the manner shown in Fig. 1. The layers 10, 11 and 12 are then connected to each other at the bottom edge B and at the upstanding edges E, by supplemental stitches 14a, which are parallel to stitches 14. The chains 13 at each corner C are thus frictionally clamped or held in position. Each chain 13 is then located between the body of layer 12, and the inturned edge-portion of said layer 12.

In each embodiment illustrated in Figs. 4 and 8, the layer 11 may be the outer layer or the inner layer of the finished face-band F, so that either the layer 10 or the layer 11 may be the face layer of the face band F of the completed collar which is shown in Fig. 9. In this completed collar, the face band is connected at its top to the top of the neckband in any suitable manner, so that the collar has a top fold-line. Each chain produces a bulge at the respective part of the finished face-band.

In the third embodiment, each flexible chain 13 is initially enclosed between the layers 15a of a flexible tape 15 by means of longitudinal stitches 16. Each chain 13 is thus frictionally held in the pocket of the respective tape 15. The layers 15a are integral at one end of said pocket. At the other end of said pocket, the layers 15a are connected by lateral stitches 17. Each chain 13 and its tape 15 are freely bendable, as a sub-unit.

In the turned and finished face-band F which is illustrated in Fig. 13, each said sub-unit abuts an exterior face of the layer 11. Stitches 14, which coincide with stitches 16, connect the edge-portions of the elements or parts of the finished face-band. As in the previous embodiments, either the layer 11 or the layer 10 may be the outer or face layer of the face-band in the completed collar.

In making the third embodiment, the layers 10, 11 and 12 can be first stitched to each other by one or more rows of stitches along edges B and E, and the assembly can then be turned so as to locate layer 12 between layers 10 between layers 10 and 11.

Each said sub-unit 13—15 can then be applied to a respective edge portion of the layer 10, and each said sub-unit can then be connected to the edge portions of said layers, at each corner C by additional stitches which pass through the fabric layers 15a and which miss the chain 13.

The links or bars of each chain 13 can be made of metal or other suitable material.

The weight of the two chains 13 at each corner C, hold each corner portion of the face band in straight and extended formation, as in a starched collar. However, each corner portion of the face band remains freely bendable, to the same extent or almost to the same extent as though the chains 13 were omitted. The bottom chains 13 are designated as "chain means." The chains 13 may produce a local stiffening effect. Each chain is therefore a bendable reinforcing member, since it may impart a local stiffening effect, and it increases the thickness of the face band, at the area where the respective chain is applied.

The length of each upstanding chain is equal to or a little less than, the length of the respective upstanding edge E. The chain 13 which follows the bottom edge B at each corner C, may

be longer than the length of the edge E, in any desired excess length. The bottom chains 13 thus hold the bottom edge B down, thus preventing undesirable wrinkling or curling effects.

The invention includes a collar in which the upstanding chains 13 are omitted, although it is preferred to use said upstanding chains. In each embodiment, the longitudinal edges of each chain or reinforcing member, are located between the longitudinal edges of the inturned edge-portions at the respective free edge of the neckband. In each embodiment, each chain or reinforcing member is held clamped to the face-band by two rows of stitches, between which the longitudinal edges of the reinforcing member are located. The reinforcing members are therefore free from stitches, between the longitudinal edges of said reinforcing members.

We have disclosed preferred embodiments of our invention, but numerous changes and omissions and additions can be made without departing from the scope of our invention.

The part of the edge-portion of the collar which is provided with the chain, can be bent into curved form, with the corner C touching the face-band of the collar, at the respective opposite end of the respective chain. The chain then imparts resilience to the respective edge-portion, so that said edge-portion springs back into straight-line shape, or substantially to straight-line shape, when said corner C is released. If said edge-portion is straightened, it keeps its shape. The links of the chain have a flattened shape. We thus increase both the weight and resilience of the face-band at its respective edge-portions, without using any springs or the like.

We claim:

1. A collar which comprises a face-band which is connectable to a neckband, said face-band having a free bottom edge and two free upstanding edges which join said bottom edge at two respective corners, transversely bendable chain means connected to said face-band adjacent said bottom edge, said chain means having longitudinal edges and having respective ends thereof adjacent respective corners of said face-band, said chain means consisting of pivotally connected links which are freely transversely movable relative to each other from end to end of said chain means, said chain means being sufficiently heavy to hold the respective part of the face-band in extended shape, said chain means being sufficiently bendable to permit said collar to be laundered without removing said chain means, said chain means being held clamped to said face-band by stitches between which the longitudinal edges of said chain means are located, said chain means being free from stitches between their longitudinal edges.

2. A collar which comprises a face-band which is connectable to a neckband, said face-band having a free bottom edge and two free upstanding edges which join said bottom edge at two respective corners, transversely bendable chain means clamped to said face-band adjacent said bottom edge, said chain means having longitudinal edges and having respective ends thereof adjacent both said corners of said face-band, said chain means consisting of pivotally connected links which are freely transversely movable relative to each other from end to end thereof, said chain means being sufficiently heavy to hold the respective part of the face-band in extended shape, said chain means being sufficiently bendable to permit said collar to be

laundered without removing said chain means, said face band having an upstanding chain of the aforesaid construction clamped thereto at each said upstanding edge thereof, each said upstanding chain having one end thereof adjacent a respective corner of said face-band, said chain means and said upstanding chains being held clamped to said face-band by respective stitches between which the longitudinal edges of said chain means and of said upstanding chains are respectively located, said chain means and said chains being free from stitches between their longitudinal edges.

3. A collar which comprises a face-band which is connectable to a neck-band, said face-band having a free bottom edge and two free upstanding edges which join said bottom edge at two respective corners, chain means clamped to said face-band adjacent said bottom edge, said chain means having longitudinal edges and also having respective ends thereof adjacent both respective corners of said face-band, said chain means consisting of pivotally connected links which are freely transversely movable relative to each other from end to end thereof, said chain means being sufficiently heavy to hold the respective part of the face-band in extended shape, said chain means being sufficiently bendable to permit said collar to be laundered without removing said chain means, said chain means being substantially as freely bendable as the material of said face-band, said chain means being

clamped to said face-band by stitches between which said longitudinal edges are located.

4. A collar which comprises a face-band which is connectable to a neckband, said face-band having a free bottom edge and two free upstanding edges which join said bottom edge at two respective corners, transversely bendable chain means connected to said face-band adjacent said bottom edge, said chain means having longitudinal edges and having respective ends thereof adjacent said respective corners, said chain means consisting of pivotally connected links which are freely transversely movable relative to each other from end to end thereof, said chain means being sufficiently heavy to hold the respective part of the face-band in extended shape, said chain means being sufficiently bendable to permit said collar to be laundered without removing said chain means, said face-band having an upstanding chain of the aforesaid construction clamped thereto at each said upstanding edge thereof, each said upstanding chain having one end thereof adjacent a respective corner, said chain means and said upstanding chains being substantially as freely bendable as the material of said face-band, said chain means and said upstanding chains being clamped to said face-band by respective stitches between which their longitudinal edges are located.
